RIGIDIZED METALLIC SHEET MATERIAL

Frank W. Broderick, New Providence, N. J., assignor to
Modern Engraving & Machine Co., a corporation of
New Jersey

Application December 30, 1955, Serial No. 39,533

Term of patent 7 years

(Cl. D54—2)

Fig. 1

Fig. 2

Fig. 1 is a plan view of a rigidized metallic sheet material showing my new design; and

Fig. 2 is an end view thereof.

The design consists of staggered rows of blunt-end raised figures similar in configuration to bowling pins, the exposed face of each figure being tapered downwardly at each side of its longitudinal center, each area between the ends of directly opposed figures of each row being separated by two short bars of a width about the same as the widths of the ends of the figures.

I claim:

The ornamental design for a rigidized metallic sheet material, as shown and described.
